B. E. MELTON

HEADLIGHT

Filed June 1, 1926

UNITED STATES PATENT OFFICE.

BURTON E. MELTON, OF SAN FRANCISCO, CALIFORNIA.

HEADLIGHT.

Application filed June 1, 1926, Serial No. 112,949.

The present invention relates to improvements in headlights for vehicles, and is ideally adapted for use in connection with motor vehicles.

5 In instances where a parabolic reflector is used in connection with reflecting the light from a vehicular headlight, the reflected rays do not always extend along lines parallel with the axis of the reflector. This is because of aberrations in the surface of the reflector or a lack of proper relation between the source of light and the focus of the reflecting surface. When either of these conditions operates to cause the reflected rays 10 to extend upwardly and outwardly, such rays enter the line of vision of the drivers of on-coming vehicles and produce what is known as glaring. Glaring headlights as is well known are objectionable and give rise 15 to dangerous conditions in traffic moving in opposite directions.

In instances where the source of light in any headlight is simply arranged in the focus of the reflector, it is obvious that considerable of the rays pass directly outward without reflection, with the result that considerable loss in the possible volume of light is had.

Coming now to the present invention, the 20 general object thereof is a headlight provided with means adapted for preventing upward and outward reflection of light rays and to provide for the reflection of all the rays from the source of light.

25 The above and other objects are accomplished by instrumentalities pointed out in the following specification.

The invention is clearly defined in the claim.

30 A satisfactory embodiment of the invention is illustrated in the accompanying drawings forming part of the specification and in which

35 Figure 1 is a vertical longitudinal section of the headlight of the present invention.

Figure 2 is a vertical cross-section on the line 2-2 of Figure 1, and looking in the direction of the arrows.

Figure 3 is an enlarged detail cross section

on the line 3-3 of Figure 1, and looking in the direction of the arrows, and

Figure 4 is a detail side elevation partly in section of the inner portion of the base of the reflecting compartment.

The casing *a* of the headlight of the present invention is preferably of metal and oblong in contour and rectangular in cross-section as shown. For the purpose of illustration I have shown the present structure attached for use in connection with a motor vehicle. It is, of course, to be understood that where the present invention is to be used in any other capacity that would require the casing to be changed in point of size or otherwise, that such change may be made without departing from the spirit of the present invention. The casing herein shown may be provided with any suitable means for attachment to a vehicle.

In the present instance I have shown a standard 5 as extending downwardly from the middle portion of the lower side and at the rear end of the casing. This standard is of a height to support the casing *a* for a suitable distance above the part to which the standard may be connected by suitable fastening devices passing through a base flange

6. *b* indicates generally the body of the reflector of the present invention. This body is so constructed that its reflecting surface 7 is made up of a plurality of sections 22, each section being a portion of a semi-parabolic surface in longitudinal section and semi-circular in cross section. As shown the body *b* is oblong and is arranged within

casing *a*, the lower opposite sides 8 and 9 of the body bearing upon the lower side 10 of casing *a*. In that the said lower side is not a reflector, it is obvious that there can be no upward or outward reflection of light rays where the reflecting surface 7 is properly constructed so as to reflect light rays parallel with the axis of the reflector. Provision is made at the inner portion of the

lower side and at the inner portion of the body *b* for the reception of a socket 11 adapted for supporting an ordinary electric globe 12 with its filament 13 in the focus of

reflector *b*. In this connection it is to be noted that the inner portion of the lower side 10 is recessed as at 14 so that the filament may be arranged directly within the focus of the reflector. 15 is a hemispherical reflecting surface formed on the inner surface of a body 16 which is disposed so as to extend around the lower segment of globe 12 which extends below the lower side wall 10.

10 The forward end of body 16 is extended slightly upward, as at 17, and is adapted for supporting a body 18 provided with a curved reflecting surface 19 which is located forwardly and beyond the focus of reflector *b*.

15 It is to be noted that the surface 19 is located above the lower side 10 of the casing and is arranged so as to intercept the rays of light extending directly forward and outward from the filament and to direct these rays upon the surface 7 of the reflector *b*.

20 In that the location of body 18 is beyond the focus of reflector *b*, it is obvious that the rays reflected by the body 18 will be reflected downwardly and outwardly by the surface 7, as shown by dotted lines in Figure 1, and as indicated by 20. The downwardly and outwardly reflected rays 20 serve to illuminate the roadway directly in front of the vehicle to which the headlight is attached, while the rays which are reflected forwardly and parallel with the axis of the reflector, and as indicated by 21, operate in the usual manner to illuminate the area far in advance of the vehicle.

25 The provision of reflecting surface 15 operates to reflect the light rays which extend downwardly and outwardly from the filament and direct these light rays upon the rear portion of reflecting surface 7, from whence they are again reflected outwardly and forwardly in the ordinary manner. It is to be noted that the supplemental reflecting surfaces provided by the reflecting surfaces 15 and 19 operate to prevent any loss in the amount of reflection on the part of surface 7, and thereby prevent the direct rays from the filament from moving forwardly and outwardly.

30 It is to be noted that body *b* conforms substantially in contour to the shell of a semi-paraboloid and while any preferred construction may be used for the shell, I have found it expedient to construct the same of sections, each of which is made up of a strip of metal with a silvered reflecting surface. The strips which are indicated generally by 22 are oblong and have converging sides. In the drawings I have shown the middle strip 23 extending through the middle portion of casing *a* with its opposite side portions underlapping the adjacent sides of adjacent strips 24. The remote sides of strips 24 underlap adjacent sides of adjacent strips 25, and the remote sides of the latter underlap strips 26. The strips 27 adjacent to the strips 26 have their opposite sides overlapping remote sides of strips 26 and strips 28, and a second series of strips 29 with their adjacent side portions lapping one another form downward continuations 70 of the body *b* from the strips 28. In that the outer ends of the strips are in a common plane and bear substantially upon the lens 30 forming the closure for the outer end of the casing *a*, it is obvious that the lengths of the strips to either side of the central strip 23 are graduated and progressively increase in length to and including the strips 27, while the remainder of the strips extending downwardly from the strips 27 progressively decrease in length.

35 The body 16 may be formed of metal and shaped as shown and of a size to form a closure for a portion of recess 14. For convenience the body 16 may be hinged as at 30' so as to open downwardly and rearwardly and afford access to the globe 12 through the recess 14. When in its operative position, the body 16 may be latched to a sliding latch plate 31 arranged in a guide 32 on the lower face of the lower side wall 10 and disposed so as to extend over the portion of the recess 14 beyond the body 16 and form a closure therefor, the engaged end of the latch being adapted to enter a detent or recess in the forward end of the body 16 as shown in Figures 1 and 4. The body 18 forming the second supplemental reflector may be of metal as shown. This body is preferably oblong in contour and has a compound curvature in transverse section. For supporting the sections 22 of the reflector use may be made of a pair of transversely disposed yokes 33 disposed transversely within the casing *a* and formed of metal. As shown two of these yokes are employed and located adjacent to the opposite ends of the body *b* and disposed transversely of the outer surface thereof made up of the outer surface of the strips 22. The inner side portions of the yokes are provided with a plurality of recesses 34 for receiving the strips 22. The recesses are arranged in echelon to either side of a centrally disposed lug 35 in order to accommodate the arrangement of the strips 22. Each strip 22 as will be noted in Figures 1 and 3 is provided in the middle portion of its outer surface with spaced lugs 36 and 37 which bear on the shoulders at the inner ends of the recesses 34 and suitable fastening devices, such as screws 38, are screwed through openings in the lugs and into the shoulders, as shown in Figures 1 and 3. With this construction the strips are rigidly held against displacement and vibration.

40 The lens 30 is secured by the usual frame 39 and fastening devices, such as screws 40, screwed into a shoulder 41 formed in the outer end of the casing.

Although I have shown and described one embodiment of my invention, it is to be understood that the same is susceptible of various changes; and I reserve the right to employ such as may come within the scope of the appended claim.

I claim:

A headlight comprising a casing having a rectangularly-shaped opening, a source of

light disposed in said casing, and a plurality of parabolic-shaped strips mounted in said casing, each strip extending from a point adjacent to the source of light to the open end of said casing, said strips being off-set to outline a substantially rectangular opening that coincides with the opening in said casing.

BURTON E. MELTON.
